UNITED STATES PATENT OFFICE.

WILLIAM HENRY MORGAN, OF ALLIANCE, OHIO.

CAST METAL WHEEL.

1,414,661.

Specification of Letters Patent. Patented May 2, 1922.

Application filed May 25, 1921. Serial No. 472,369.

To all whom it may concern:

Be it known that I, WILLIAM H. MORGAN, a citizen of the United States, and a resident of Alliance, in the county of Stark and State of Ohio, have invented certain new and useful Improvements in Cast Metal Wheels; and I do hereby declare the following to be a full, clear, and exact description of the invention, such as will enable others skilled 10 in the art to which it appertains to make and use the same.

My invention relates to an improvement in cast metal wheels designed particularly for self propelled vehicles and it consists in 15 a cast metal wheel the spokes of which are shaped to provide for lateral strength whereby breaking or dishing of the wheel is prevented when the machine skids or in rounding a curve or when the wheels strike 20 a curb. It further consists in a wheel having spokes so shaped as to act as fan blades and assist in cooling the brake drum and 25 brake band. It further consists in details of construction as will be more fully explained and pointed out in the claims.

In the accompanying drawings, Figure 1 is a view in side elevation of the rear wheel of an automobile, part of it being broken away, and the brake drum being shown in 30 dotted lines; Figure 2 is a view in section of the same the brake drum being shown in full lines; Figure 3 is a transverse section of one of the spokes; Figure 4 is a view in elevation of a front wheel of the type shown in 35 Figures 1 to 3, and Figures 5 to 11 inclusive are views of slightly modified forms of wheels.

The wheel comprises a felly 10, hub 11 and spokes 12 all cast integral. The spokes 40 are elliptical in cross section with their long diameters extending transversely of the wheel as shown in Figures 1 and 2, thus distributing the metal so as to provide for great lateral strength and prevent dishing of the 45 wheel when the machine skids or when subjected to great lateral stresses such as occurs when it is turning a curve, or when the wheels strike a curb or other obstruction. Spokes so shaped and having comparatively 50 flat and wide front and rear faces also act as fan blades for cooling the brake and drum 15 of the rear wheel, and being of metal have a greater factor of conductivity for heat and hence a tendency to conduct the 55 heat away from the brake drum and thus keep it cool.

In the construction shown in Figures 1, 2 and 4 each spoke has an integral enlarged boss 13 at its juncture with the felly for the passage of the bolts for attaching the 60 demountable rim or tire holding clips in place and each rear wheel as shown in Figures 1 and 2 is also provided intermediate its ends, and about midway thereof with an enlargement 14 having a drilled opening there- 65 through for the passage of the bolts which secure the brake drum 15 to the wheel. As shown in Figure 2 these enlargements 14 project at the inner edges of the spokes to 70 form bearings for the brake drum 15, thus leaving spaces 16 between the drum and spokes for the free circulation of air which of course materially assists in keeping the brake drum cool.

The felly 11 is provided with a hole 17 75 for the passage of the air pipe communicating with the inner tube of the tire, not shown.

The construction shown in Figure 4 represents the front wheel of an automobile 80 and is identical with that shown in Figures 1, 2 and 3 except that it is not provided with a brake drum, or the spoke enlargements for the attachment of a drum.

The wheel shown in Figure 5 is identical 85 with that shown in Figure 1 except that each alternate spoke is provided with a drilled boss 13 for the attachment of the demountable rim or tire clip, and the enlargement for the brake drum bolts are nearer the hub, 90 the latter construction being designed particularly for Ford cars.

In Figures 6 and 7 I have shown rear wheels provided with brake drum cast integral with the spokes. In other respects they 95 are identical with the construction shown in Figure 5. The front wheels to be used with the wheels shown in Figures 5, 6 and 7 are identical with Figure 4 except that the bosses 13 for the demountable rim holding 100 clips are in each alternate spoke as in Figure 5 instead of in each spoke.

In the construction shown in Figures 8 to 11 inclusive, the spokes are of S-shape. Spokes of this shape are more resilient than 105 straight spokes, and in case the rim or felly shrinks while cooling, the spokes will give or bend without breaking. The advantage of the spokes, elliptical in cross section, with their long diameter transversely of the 110 wheel, in addition to adding lateral strength as above explained, are that there are no

recesses or projections to collect dirt; are readily and easily cleaned and owing to the side spaces between them due to flattening, permit of ready access to the brake band 5 for adjusting and repairing same.

The wheels as previously explained are all cast in one piece and then thoroughly annealed to remove all cooling strains and change its crystalline structure so that they 10 will bend or yield and not readily shatter when subjected to a blow. A wheel so constructed is decidedly stronger than, weighs less than a wood wheel of the same size which latter is composed of about seventy- 15 four pieces (where the brake is made separate); are less expensive to manufacture, and can be enameled to resemble the wood wheels in use, or can be nickel plated and polished.

20 Having fully described my invention what I claim as new and desire to secure by Letters-Patent, is:—

1. As a new article of manufacture, a wheel comprising a hub, spokes, and full 25 width felly all cast integral, the spokes being elongated transversely in cross section and located approximately central with relation to the full width felly and enlarged bosses at the juncture of the spokes and 30 felly having openings therethrough for the passage of the rim securing bolts.

2. As a new article of manufacture, a wheel comprising a hub, spokes and full 35 width felly all cast integral, the spokes being elongated transversely in cross section, and provided with integral enlarged bosses intermediate of the hub and felly, and integral enlarged bosses at their juncture with the felly.

40 3. As a new article of manufacture, a wheel comprising a hub, spokes and felly all cast integral, integral enlarged bosses at the juncture of the spokes and felly and having openings for the passage of bolts 45 for securing the tire securing clips in place, and enlargements integral with spokes intermediate the felly and hub for the passage of

brake drum securing bolts, the said enlargements projecting inwardly from the spokes so as to hold the brake drum away from 50 the spokes thus leaving an air space between the spokes and drum.

4. As a new article of manufacture, a wheel comprising a hub, spokes and felly all cast integral, the spokes being elliptical 55 in cross section, integral enlarged bosses at the juncture of spokes and felly and having openings for the rim securing bolts, and enlargements integral with spokes intermediate the felly and hub to receive the brake 60 drum securing bolts, the said enlargements projecting inwardly from the spokes to hold the brake drum away from the latter.

5. As a new article of manufacture, a wheel comprising a hub, spokes and felly 65 all cast integral, the spokes being curved longitudinally and elliptical in cross section the long diameter of the spokes extending transversely of the wheel, and enlarged bosses integral with the spokes and felly at 70 the juncture of the spokes with the felly for the attachment of the rim securing clips.

6. As a new article of manufacture, a wheel comprising a hub, spokes and felly all cast integral, the spokes being curved 75 longitudinally and provided at their juncture with the felly with enlarged bosses, and at points between the felly and hub with enlargements for the passage of brake drum securing bolts.

7. As a new article of manufacture, a wheel comprising a hub, spokes and felly all cast integral, the spokes being curved longitudinally and elliptical in cross section, with their long diameters transversely of the 85 felly.

In testimony whereof, I have signed this specification in the presence of two subscribing witnesses.

WILLIAM HENRY MORGAN.
